UNITED STATES PATENT OFFICE.

HENRY F. HAYDEN, OF WASHINGTON, DISTRICT OF COLUMBIA.

IMPROVEMENT IN HOT-AIR FURNACES.

Specification forming part of Letters Patent No. 156,568, dated November 3, 1874; application filed September 29, 1874.

To all whom it may concern:

Be it known that I, HENRY F. HAYDEN, of the city and county of Washington, District of Columbia, have invented certain new and useful Improvements in Hot-Air Furnaces; of which the following is a full, clear, and exact description, reference being had to the accompanying drawing, making part of this specification, in which—

Figure 1 represents a plan or top view of my improved heater, with the top of the casing removed. Fig. 2 is a perspective view of a portion of the inclosing casing, showing the inner side of said casing. Fig. 3 is a section through one of the smoke-flues. Fig. 4 is a vertical section on the line $x\ x$, Fig. 5; and Fig. 5 is a bottom view.

Similar letters of reference denote corresponding parts wherever used.

My invention relates to a novel construction and arrangement of parts of the furnace or heater, whereby a large amount of radiating surface, heated in a mild form, is secured, all highly-heated surfaces in the heating-chamber avoided, and the products of combustion very largely utilized for heating purposes before they are allowed finally to escape into the smoke-flue or chimney, as hereinafter explained. It further relates to a novel construction and arrangement of vaporizing attachment, whereby the usual objection to this class of heaters, caused by the dryness of the heat emitted, is effectually obviated, as hereinafter fully set forth.

In the accompanying drawing, A represents the external casing or walls of the heating-chamber, which may be made of any usual material and of any desired form or configuration. Within this is placed the furnace or heater proper, consisting, in the main, of two parallel rectangular compartments or chambers, B C, connected by direct and return flues $b\ c$. Within the chamber B is located the fire-pot and ash-pit, with the intermediate grate D, the walls $E\ e^1\ e^2$ of said fire-pot and ash-pit being made of fire-brick, cast-iron, or any usual or preferred material. The front, rear, and one side wall, $e^1\ e^2$, of the fire-box terminate a short distance above the fuel-chute F, as shown in Fig. 4, leaving the fire-pot open on top, while the wall E extends from the bottom to the top of the compartment or chamber B, forming a

tight partition therein, giving two separate compartments, $B^1\ B^2$, from the latter of which the products of combustion, escaping from the open top of the fire-pot, are excluded, except as hereinafter explained. The compartment B^1 , into which the products of combustion pass from the fire-pot, is connected with the compartment or chamber C by a number of horizontal flues, b , and the compartment C again is partially divided by a partition piece or plate, C', extending from the top downward to a point midway, or thereabout, the height of said compartment, and underneath which the escaping products of combustion are compelled to pass, and said products of combustion are conveyed thence, through return-flues c , to the chamber B^2 of compartment B, from which they are permitted to escape through a smoke-flue, G, which conducts them to any desired point of discharge. The flues $b\ c$ are, by preference, made elliptical in form, as shown in Fig. 3, as affording a larger amount of radiating surface, and the joints thereof, as also all those of the compartments B C, may be covered with cement for preventing the escape of gas into the hot-air chamber, or, if preferred, the entire outer surface of the compartments B and C, and of the flues inside the hot-air chamber, may be covered with a thin coating of cement, effectually preventing the escape of gas without interfering with the radiation of heat. Where any portion of the surface of the flues or of the chambers would be liable to be brought to a red heat the coating of cement should be increased in thickness, so as to protect the hot-air chamber from the injurious effects of such heat.

In the arrangement above described it will be seen that the gaseous products of combustion, escaping from the open top of the fire-pot, first enter the compartment or chamber B^1 , whence they pass through the flues b to the compartment C, upon one side thereof, under the partition-plate C', to the opposite side, and through return-flues c to the compartment B^2 , and thence out through the smoke-flue G, parting at each step or stage of their progress with more or less of their heat, which is transmitted through the extended surface of said compartments to the air in the surrounding compartment until the temperature of the unconsumed gases is reduced to nearly or quite

the temperature of the atmosphere in said hot-air compartment, when they are allowed to escape, as explained.

For causing the atmospheric air admitted to the hot-air chamber A' to pass inward among the flues b and c, and in close proximity to the chambers B and C, deflectors a a' are secured to the inner faces of the walls A, these deflectors passing horizontally around the hot-air chamber, and those, a', at the bottom, where the air is supplied in any usual way, forming a cold-air conduit around the bottom of the heating-chamber, and from which the air passes into the chamber through slits or perforations a*. The deflector a runs in a similar manner around the hot-air chamber, in close proximity with the upper portion of the furnace, and prevents the cold air from ascending in right lines through the annular space between the furnace and its casing, causing it to be deflected inward among the transverse flues b c, and into contact or close proximity with the heating-surfaces.

For the purpose of moistening the air as it is heated, and obviating the objections heretofore common to hot-air furnaces on account of the dry character of the heat produced, a large evaporating-pan, H, is placed at the bottom of the heating-chamber, between the rectangular chambers B C, filling, if desired, the entire space between the bottoms of said chambers, and supplied with water in any convenient way.

I is a rod or wire, extending across between the chambers B and C, at or near midway of their length, and from this rod is suspended a sheet of wire-gauze, K, made by preference of brass or galvanized wire to prevent corrosion, bent midway of its length, with its folded center resting on the rod I, and its ends reaching down into the evaporating-pan H. Within this folded sheet of wire-gauze is secured a layer or sheet of sponge, or equivalent material, which will, by its capillary attraction, become saturated with water from the pan H, while, at the same time, it is not liable to be injured by the heat when dry. This evaporating or vaporizing sheet is, by preference, suspended between the direct flues b and the return-flues c, where the heat is greatest, and the best effect will be produced; but it may, of course, be differently located, as convenience or the requirements of the furnace may dictate.

By this arrangement it will be seen that, when the sponge becomes saturated, a large surface of water is exposed to the ascending volume of air, and the air, as it is heated, is thereby thoroughly moistened before it escapes from the heating-chamber, and from which it is conveyed to the rooms to be heated in any usual or preferred manner.

The chambers B and C are provided with man-holes at m n, closed by suitable doors, which afford access to the chambers and flues for cleaning and repairs.

In practice, the furnace proper, as above described, should be first set up, and connection of the smoke-flue made with the desired outlet, after which a fire should be built in it, for the purpose of testing all the joints, and, while thus heated, the coating of cement should be applied to all the joints, as well as to such parts of the apparatus as would be at all liable to be brought to a red heat, under any conditions of use; and, thus applied, all danger of the cracking or flaking off of the coating of cement is effectually avoided, while, at the same time, the apparatus is in condition for best ascertaining all leakage in the joints, and for applying the remedy. After this is done, the walls or casing of the heating-chamber may be built up around the furnace in any usual or preferred manner, and of any suitable material.

The walls or sides of the chambers B and C and the flues b c may be all of sheet metal, this being protected in the portions most exposed to the direct heat of the fire by the fire-brick or cast-iron of which the fire-pot is composed, and by the coating of cement, as explained.

I am aware that water has been carried up by mechanical appliances for the purpose of extracting dust from, and imparting moisture to, the atmosphere; but, in these appliances, so far as I am acquainted with them, the action was necessarily arbitrary and unvarying; while, with my evaporating apparatus, the conditions vary with the varying conditions of the atmosphere. Thus, when a high degree of heat is imparted to the atmosphere, and a rapid evaporation of the water exposed is produced, a corresponding increase takes place in the capillary action of the vaporizer, and vice versa, the amount of evaporation being at all times in proportion to the degree of dryness of the atmosphere, this effect being due to the porous nature of the sponge, upheld by the open wire-gauze, and in which, as the moisture is extracted, a constantly-increasing surface is exposed to the action of the surrounding atmosphere.

Having now described my invention, what I claim as new, and desire to secure by Letters Patent, is—

1. The divided rectangular compartment B, inclosing the fire-pot and ash-pit, as explained, in combination with the partially-divided compartment C and direct and return flues b c, all constructed, arranged, and operating substantially as and for the purpose specified.

2. The vaporizing apparatus composed of the evaporating-pan H and of the wire-gauze and sponge, in combination with the furnace, arranged and operating substantially as described.

H. F. HAYDEN.
